(57) **CLAIM**

The ornamental design for an anti-free flow modulator, as shown and described.

DESCRIPTION

FIG. 1 is a front perspective view of the anti-free flow modulator showing our new design taken from the top, the dashed lines forming no part of the claimed design;

FIG. 2 is a front elevational view thereof, the dashed lines forming no part of the claimed design;

FIG. 3 is a left elevational view thereof, a right elevational view being a mirror image thereof, the dashed lines forming no part of the claimed design;

FIG. 4 is a top view thereof, the dashed lines forming no part of the claimed design; and,

FIG. 5 is a bottom view thereof.

The broken line showing of a portion of the anti-free flow modulator is included for the purpose of illustrating environmental structure and forms no part of the claimed design.
